Patented June 22, 1915.

UNITED STATES PATENT OFFICE.

JOSEPH A. WILLIAMS, OF CLEVELAND, OHIO, ASSIGNOR TO K. W. IGNITION COMPANY, OF CLEVELAND, OHIO, A CORPORATION OF OHIO.

MAGNETO DRIVING MECHANISM.

1,144,016.

Specification of Letters Patent. Patented June 22, 1915.

Application filed December 26, 1911. Serial No. 667,613.

To all whom it may concern:

Be it known that I, JOSEPH A. WILLIAMS, a citizen of the United States, residing at Cleveland, in the county of Cuyahoga and

5 State of Ohio, have invented a certain new and useful Improvement in Magneto Driving Mechanism, of which the following is a full, clear, and exact description.

The object of this invention is to provide 10 efficient means by which, when an internal combustion engine is slowly turned over, the magneto associated therewith will be compelled to give a succession of quick forward movements that will result in the production 15 of kick-off sparks in the engine cylinders; but which will become inoperative for this purpose when the engine has fairly started, and has attained a suitable speed, after 20 which the magneto will run regularly in proper synchronism with the engine.

The invention includes a spring which is 25 interposed between the armature shaft and the driving member, means for temporarily preventing the armature shaft from turning 30 while the driving member is being turned and is thereby putting the spring under tension, and means whereby when the driving member has been turned through part of a revolution, it will cause the withdrawal of 35 said holding means, and permit the tensioned spring to turn the armature shaft quickly forward until it catches up with the driving member,—said quick forward movement producing a kick-off spark in an engine cylinder.

The invention in a practically efficient 40 form is shown in the drawing, is hereinafter described, and the novel combinations of parts constituting the invention are set forth in the appended claims.

In the drawing, Figure 1 is an end elevation of the invention when the parts thereof are in the position they occupy when the engine is running. Fig. 2 is a similar view 45 showing the same parts, but in the position they occupy when the engine is being started. Fig. 3 is a central vertical sectional view.

Referring to the parts by letters, A re- 50 presents the armature shaft of the magneto.

C represents a fixture which is secured to one of the side frame members in which this shaft is journaled.

B represents the driving member which is 55 in the form of a sleeve rotatably mounted on the shaft A, and having the housing b which overhangs a sleeve D which is fixed to the shaft A. This sleeve D has a disk d which is of larger diameter than the diameter of the housing b. A volute spring F is arranged 60 within the housing b and is connected at its ends with said housing, and with the sleeve D. The disk d also carries a spring pawl E having a V-shaped end which is adapted to fit into a V-shaped notch b' on 65 the housing b.

The driving member is to be connected by suitable mechanism with the crank shaft of the engine with which the magneto is to be used. The gear H which is fixed to the 70 member B may be a part of the train of gearing which may be employed for this purpose. Under normal working conditions, the rotary motions of the driving member B will be transmitted to the armature shaft A 75 through the spring F,—the spring pawl E serving to definitely fix the relative positions of these parts.

Pivoted to the fixture C is a dog G having 80 at its free end a tooth g adapted to engage a shoulder d' formed by cutting a notch in the periphery of the disk d. This dog has above 85 its pivot an arm g' which is adapted to be engaged by one end of the latch lever J whereby the dog is held out of operative position 90 as shown in Fig. 1. The dog G has also an arm g'' which when the tooth g is engaging with the shoulder d' will lie in the path of a knockout arm K which is fixed to the housing b. In order to use this mechanism to 95 produce the kick off sparks in the engine cylinder, the operator turns the latch lever J to the position shown in Fig. 2, whereupon the dog will swing downward so that its tooth g engages the periphery of the disk D. Then the operator, as he slowly turns over 100 the engine, will turn the housing b in the direction indicated by the arrow on Fig. 2, thereby turning also the disk d until the shoulder d' thereof engages the tooth g' of

the dog G. This dog will prevent the disk D and consequently the armature shaft from turning; and as the driving member B is still further turned, the spring F will be put under tension, and this will continue until the knock-off arm K is turned around and hits the arm g^2 of the dog G. By this engagement, the dog will be pushed outward and disengaged from shoulder d' . Thereupon since the armature shaft is now free from restraint, it will be turned rapidly forward by the tensioned spring F, and this rapid movement will continue until the armature shaft has caught up with the rotatable member B. By this quick forward movement of the armature shaft, the kick off sparks will be produced. In order that the device may not be racked by this quick movement, a spring buffer M is provided. This is a short plunger which is movably mounted in a lug d^2 fixed to the disk d and projecting through this lug into a position where it may engage the kick-off arm K when the disk d has caught up with the housing b. The spring m which resists the movement of this buffer plunger which results from its contact with the kick-off arm, is also utilized to impart the required engaging movement to the pawl E, said spring being compressed between the shoulder on the buffer and the tail of the pawl E.

The described movement of the parts will be repeated as long as the engine is being slowly turned over. When, however, the engine gets fairly started and attains a suitable speed, the blows from the knock off arm K against the arm g^2 of the dog will be sufficiently forceful to swing the dog out so far that the latch J will fly down behind the upper end g' of the dog, and thereby hold it in inoperative position substantially as shown in Fig. 1.

A spring N of the rat trap variety, may be employed to impart to the latch its movement in the latching direction and also to impart to the dog some force tending to supplement the action of gravity in moving this dog to the position where it will engage with the shoulder d' .

Having described my invention, I claim:

1. The combination with the armature shaft of a magneto, of a driving member concentric with the shaft, said driving member having an enlarged cup shaped portion, a coiled spring surrounding the shaft and within said cup shaped portion of the driving member, said spring being operatively connected at opposite ends to the driving shaft and the driving member, a device for preventing rotation of the armature shaft, and means carried by the driving member for displacing said preventing device, substantially as described.

2. The combination with the armature shaft of a magneto, a concentric driving

member, a spring pawl carried by one of said members and having a beveled end which enters a beveled notch in the other member, and a spring through which motion is transmitted from the driving member to the armature shaft, of a device to temporarily prevent the turning of said armature shaft, means carried by the driving member for moving said device to an inoperative position whereby the armature shaft may move quickly forward by said spring relatively to the driving member, and a spring buffer for yieldingly stopping said forward movement of the armature shaft relative to the driving member.

3. The combination with the armature shaft of a magneto, a concentric driving member, and a spring through which motion is transmitted from the latter to the former, of a disk fixed to the armature shaft and provided with a shoulder, a dog pivoted to a fixture for engagement with said shoulder, and a knock out arm carried by said driving member and adapted to move said dog out of engagement with said shoulder.

4. The combination with the armature shaft of a magneto, a concentric driving member, and a spring through which motion is transmitted from the latter to the former, a disk fixed to the armature shaft and provided with a shoulder, a dog pivoted to a fixture for engagement with said shoulder, a knock out arm carried by said driving member and adapted to move said dog out of engagement with said shoulder, and a spring buffer carried by the disk and adapted to engage said knock out arm.

5. The combination with the armature shaft of a magneto, a concentric driving member and a spring through which motion is transmitted from the latter to the former, a disk fixed to the armature shaft and provided with a shoulder, a dog pivoted to a fixture for engagement with said shoulder, a knock out arm carried by said driving member and adapted to move said dog out of engagement with said shoulder, a buffer plunger movably mounted in a lug carried by said disk in position to engage said knock out arm, a pawl carried by said disk and having a beveled end adapted to engage a beveled notch in the driving member, and a spring interposed between said buffer plunger and pawl and acting on both.

6. The combination with the armature shaft of a magneto, a hub provided with a disk fixed to said shaft, a driving member rotatably mounted on the shaft and having a housing which overhangs said hub, a volatile spring within said housing, and having its ends fixed thereto and to said hub, said housing having a V-shaped notch in its periphery, a spring pawl mounted on the disk and having a V-shaped tooth for engaging said notch, a dog pivoted to a fixture and

having a tooth adapted to engage a shoulder on said disk, said dog also having an arm, a knock out arm fixed to said housing in a position to engage with the said arm of the dog and a spring latch adapted to automatically engage said dog and hold it in an inoperative position when it has been moved to that position by the impact of

said knock out arm against the arm of the dog.

In testimony whereof, I hereunto affix my signature in the presence of two witnesses.

JOSEPH A. WILLIAMS.
